BENJAMIN EDELMAN, OF NEW YORK, N. Y.

GARMENT PROTECTOR

Application filed September 30, 1926. Serial No. 138,715.

This invention relates to a device for protecting garments while they are kept upon the usual garment-hangers, and particularly while the garments are currently in use.

5 The principal object of the invention is to provide a simple, inexpensive, conveniently and economically manufacturable, conveniently utilizable, efficient and improved device for this purpose.

10 Other objects and advantages will herein-after appear.

In the accompanying drawings,—

Fig. 1 is a front elevation of the garment protector, showing it while in use upon the 15 garment, as the latter is supported by the garment hanger.

Fig. 2 is an end elevation of the garment protector shown in Fig. 1.

Figs. 3 and 4 show, in perspective, modifications of the garment protector.

The garment protector 1 comprises a substantially circularly-shaped sheet 2, preferably of stiff linened paper. Said sheet is folded in half, thereby forming a crease 3 that passes through its centre and providing a pair of downwardly hanging semicircular leaves 4. In the centre of the sheet 2 is formed an opening 5, preferably of substantially elliptical configuration, which opening 25 thus constitutes an outlet for the hook 6 of the garment-hanger 7, as shown in Fig. 1. The crease 3 and edge 8 of the opening 5 are reinforced by a binding 9, and the circular periphery 10 of the sheet is also reinforced 30 by a binding.

When using the garment protector it is simply slipped over the hanger 7 and garment 11, in the manner shown in Fig. 1. It will be evident that with the utilization of this 40 device the upper parts, and particularly the shoulder-parts, of the garment are fully protected from dust, and when the hangers are suspended in a row upon a rod the garments are kept separated from each other by the 45 protector-leaves 4, and the intermingling of

the garments is thereby prevented. When shifting the hangers with the garments along such rod, as when removing or replacing some of them, the garments are protected against being soiled by the hands, as the handling 50 during shifting can be done with the hands coming in contact only with the leaves 4 of the protectors instead of directly with the garments. The foregoing advantages are of particular value in ladies' dress stores, or similar 55 situations, where a large quantity of garments is currently kept in closets upon hangers suspended from rods, and the trade necessitates the constant shifting of the garments for demonstration and sale.

In the modification shown in Fig. 3, a pair of parallel creases 12 is provided, in place of the single crease 3 in Fig. 1, and a protector built according to this modification is particularly adapted for spring and winter coats, 65 whereas the protector shown in Fig. 1 is more adaptable for such garments as ladies' dresses, etc.

According to the modification shown in Fig. 4, pairs of creases 13 converge from 70 the periphery of the sheet 2 toward the opening 5, which creases provide portions 14 that are inclined and tend to follow the shapes of the shoulder-portions of the hangers and garments, and a protector of this modification is particularly adaptable for men's coats 75 and overcoats.

Variations may be resorted to within the scope of the invention, and portions of the improvements may be used without others.

Having thus described my invention, I claim:—

For use in combination with a garment hanger having a yoke and a hook projecting from the center of the yoke, a garment protector, comprising a substantially circular integral piece of flexible sheet material having a crease along the center line of the same, whereupon it may be folded and then placed on the garment hanger, its creased portion 90

resting on the shoulder portion of the garment and two depending substantially semi-circular halves protecting the front and the back of the garment, respectively, said piece of material also having an opening provided about its center to receive the projecting hook of the garment hanger, and reinforcing strips of flexible material pasted around the inner and outer edges and along the creases of said circular piece of material.

10 Signed at the city of New York, in the county of New York and State of New York, this 24th day of September, A. D. 1926.

BENJAMIN EDELMAN.
